UNITED STATES PATENT OFFICE

JAMES ELLIOTT MADDOX, OF LOUISVILLE, KENTUCKY

SMOKING PIPE WITH REMOVABLE INNER BOWL

Application filed December 1, 1928. Serial No. 323,008.

The object of my invention is to provide a novel pipe having a slidably removable inner bowl which will permit the user to clean out the pipe and insure a dry bottom 5 pipe at all times, thereby producing a more enjoyable smoke as the "gummy substance" which accumulates in pipes causes a disagreeable taste and prevents the real taste of the tobacco from reaching the mouth and 10 which taste is desired by pipe smokers.

It is further a purpose of my invention to provide means for sliding the bowl whereby a well fitting bowl and one that would be durable could be made and utilized in a 15 pipe of high grade.

I attain these and other objects of my invention by the mechanism illustrated in the accompanying drawings, in which,—

Figure 1 is a top plan view of the invention;

Fig. 2 is a longitudinal section on line 2—2 of Fig. 1; and

Fig. 3 is a perspective view of the pipe with the inner bowl removed.

Like numerals designate like parts in each of the several views.

Referring to the accompanying drawings I provide an outer bowl 1, pipe stem 2 and detachable mouth piece 3. The mouth piece 20 is provided with the usual smoking channel 4 and the pipe stem with a smoke channel 5 connecting with a smoke channel 11 opening into the tobacco chamber 9 of the inner bowl 8. The outer bowl 1 is provided 25 with a chamber 6 to slidably receive the inner bowl 8. The outer bowl is also provided with the opposite transversely extending grooves 7 of dovetail shape in cross section in which the correspondingly shaped 30 ribs 10 of the inner bowl 8 slidably seat. The inner bowl 8 has the tobacco chamber 9 at the bottom of which is an outlet 12 in the inner bowl, as shown in Figs. 1 and 2.

To clean the inner bowl it is necessary to 45 slide it all the way out, as shown in Fig. 3, in which position the outlet or opening 12 can readily be cleared of the undesirable bottom tobacco, tar, etc. by using a match, nail, pencil or the like as a sort of push 50 poker.

What I claim is:

1. In a smoking pipe, the combination of an outer bowl having a chamber extending from side to side thereof, said chamber including transversely extending grooves, 55 and an inner bowl slidable by means of transverse projections engaging in corresponding grooves in the outer bowl and having ribs corresponding with the grooves to slidably hold the inner bowl firmly in place 60 in the outer bowl, said inner bowl having an outlet in the bottom thereof for the discharge of waste products of smoking tobacco.

2. In a smoking pipe, the combination of 65 a chambered outer bowl, an inner bowl slidably mounted in the chambered outer bowl, the outer bowl having transverse grooves of dovetail shape in cross section, and the inner bowl having projecting ribs of similar disposition and of dovetail shape in 70 cross section to slidably engage the grooves of the outer bowl.

3. In a smoking pipe, the combination of 75 an outer bowl chambered to receive an inner bowl, said chamber extending all the way across from one side to the other of the outer bowl, an inner bowl slidably mounted in said outer bowl, means for holding said bowls interlocked when seated one 80 in the other, the inner bowl having an outlet in the bottom thereof for the purposes described.

4. In a smoking pipe, the combination of 85 an outer bowl having a channeled pipe stem, a channeled mouth piece detachably mounted on the pipe stem, an inner bowl laterally slidably into and out of the outer bowl, said inner bowl having a channel communicating 90 with the channel in the pipe stem, said inner bowl also having a discharge outlet in the bottom thereof for the discharge of waste products of tobacco, and means for frictionally holding the inner bowl firmly but 95 slidably seated in the outer bowl.

JAMES E. MADDOX.
